SHUFFLEBOARD ATTACHMENT

Arthur Raymond, Seattle, Wash., assignor of one-half to K. E. Schultz, Seattle, Wash.

Application February 26, 1953, Serial No. 23,800

Term of patent 7 years

(Cl. D34—5)

To all whom it may concern:

Be it known that I, Arthur Raymond, a citizen of the United States of America, residing at Seattle, in the county of King and State of Washington, have invented a new, original, and ornamental Design for a Shuffleboard Attachment, of which the following is a specification, reference being had to the accompanying drawings, forming part thereof.

Fig. 1 is a top plan view of a shuffleboard attachment, showing my new design.

Fig. 2 is an elevational view of the same.

Fig. 3 is an end view thereof.

Fig. 4 is a sectional view taken on line 4—4 of Fig. 1.

Fig. 5 is a perspective view thereof.

I claim:

The ornamental design for a shuffleboard attachment, as shown.

ARTHUR RAYMOND.
